SPEAKER CONTROL UNIT

Kenneth A. Everhart, 3901 W. 67th St.,
Prairie Village, Kans.

Filed May 14, 1965, Ser. No. 85,275

Term of patent 3½ years

(Cl. D26—13)

FIG. 1 is a front elevational view of a speaker control unit, showing my new design;

FIG. 2 is an elevational view of the right side of the speaker control unit, the left side thereof being a mirror image of the right side;

FIG. 3 is a rear elevational view thereof;

FIG. 4 is a bottom plan view thereof; and

FIG. 5 is a top plan view of the speaker control unit.

I claim:

The ornamental design for a speaker control unit, as shown and described.
